UNITED STATES PATENT OFFICE

149,922

DESIGN FOR A WRITING INSTRUMENT

Alexander Sydney Weston, New York, N. Y.

Application April 24, 1947, Serial No. 138,570

Term of patent 3½ years

(Cl. D74—24)

To all whom it may concern:

Be it known that I, Alexander Sydney Weston, a citizen of the United States, residing at New York, in the county and State of New York, have invented a new, original, and ornamental Design for a Writing Instrument, of which the following is a specification, reference being made to the accompanying drawing, forming a part thereof.

Fig. 1 is a front elevational view of a writing instrument showing my new design.

Fig. 2 is a rear view of the cap portion thereof; and

Fig. 3 is an elevational view of the body portion thereof.

The essential features of my design reside in the parts shown in full lines.

I claim:

The ornamental design for a writing instrument as shown and described.

ALEXANDER SYDNEY WESTON.
